UNITED STATES PATENT OFFICE.

FREDERIC H. MANCHESTER, OF PROVIDENCE, RHODE ISLAND, ASSIGNOR TO
THE PROVIDENCE GAS BURNER COMPANY, OF SAME PLACE.

DESIGN FOR A CONTACT-RING FOR INCANDESCENT-LAMP BASES OR CAPS.

SPECIFICATION forming part of Design No. 34,174, dated March 5, 1901.

Application filed February 7, 1901. Serial No. 46,448. Term of patent 14 years.

To all whom it may concern:

Be it known that I, FREDERIC H. MANCHESTER, a citizen of the United States, residing at Providence, in the county of Providence and State of Rhode Island, have invented and produced a new and original Design for a Contact-Ring for Incandescent-Lamp Bases or Caps, of which the following is a specification, reference being had to the accompanying drawings, forming part thereof.

Figure 1 is a perspective view of my newly-designed contact-ring for incandescent-lamp bases or caps. Fig. 2 is a plan view of the same as seen from below. Fig. 3 is a side view of the contact-ring.

As shown in the drawings, the leading and material features of my design consist of the posts *a a*, extending from the inner margin of the ring *b*, and the depression *c* in the ring

b. The posts *a a* extend beyond the lower 20 surface of the ring and the depression *c* extends below the upper or contact surface of the ring *b*. Conductor-terminals may be secured in the depression *c* below the contact-surface of the ring. 25

Having thus described my invention, what I claim as new, and desire to secure by Letters Patent, is—

The design for a contact-ring for incandescent-lamp bases as herein shown and described. 30

In testimony whereof I have signed my name to this specification in the presence of two subscribing witnesses.

FREDERIC H. MANCHESTER.
